(57) **CLAIM**

The ornamental design for a double shelving system with hidden compartments, as shown and described.

DESCRIPTION

This invention relates to the following applications, filed on the even date herewith, and herein incorporated by reference: U.S. Ser. No. 29/469,902, entitled Table with Hidden Compartments, by Matthew B. Dworman; U.S. Ser. No. 29/469,900, entitled Cabinet with Hidden Compartments, by Matthew B. Dworman; U.S. Ser. No. 29/469,898, entitled Shelving System with Hidden Compartments, by Matthew B. Dworman; and U.S. Ser. No. 29/469,897, entitled Desk with Hidden Compartments, by Matthew B. Dworman.

FIG. 1 is a perspective view of a double shelving system of my new design, the double shelving system having hidden compartments and shown with its compartments being in a closed condition;

FIG. 2 is a front elevational view thereof;

FIG. 3 is a side elevational view thereof as viewed from its left side, with the right side being a mirror image thereof;

FIG. 4 is a rear elevational view thereof;

FIG. 5 is a bottom elevational view thereof;

FIG. 6 is a top elevational view thereof;

FIG. 7 is a perspective view of the double shelving system of FIG. 1 with its compartments shown in an open condition;

FIG. 8 is a front elevational view of the double shelving system of FIG. 7;

FIG. 9 is a side elevational view of the left side of the double shelving system of FIG. 7;

FIG. 10 is a side elevational view of the right side double of the shelving system of FIG. 7;

FIG. 11 is a top elevational view of the double shelving system of FIG. 7; and,

FIG. 12 is a bottom elevational view of the double shelving system of FIG. 7.
